UNITED STATES PATENT OFFICE

AUGUSTUS C. DURDIN, JR., OF CHICAGO, ILLINOIS

VACUUM CONDENSATION PUMP

Application filed April 29, 1931. Serial No. 533,755.

This invention relates to vacuum condensation pumps and is in the nature of an improvement on the vacuum condensation pump shown and described in my former Patent No. 5 1,775,425, dated September 9, 1930.

The present invention has been designed particularly for use in steam heating plants, although its use is not limited thereto, and it is arranged to be connected with the returns 10 of the plant and operates to separate air and other non-condensable gases from the water of condensation and return the water back to the boiler or other place. It is well known that considerable vapor is returned with 15 the water of condensation, which vapor usually occupies the upper portion of the receiver or collection tank, and one of the objects of the present invention is to mix the vapors with the water of condensation, where- 20 by the vapors will be condensed, thereby caus- ing a partial vacuum in addition to the vacuum produced by the vacuum pump itself.

In the apparatus of my prior patent, above referred to, a water pipe and an air pipe were 25 employed between the receiver and the vacuum chamber of the pump, and one of the objects of the present invention is to provide a single conduit through which both the wa- 30 ter of condensation and the vapors as well as the air and other non-condensable gases may be withdrawn from the receiver. Another object is to provide automatically acting 35 means in a vacuum condensation pump of the present type, whereby in case the water en- 40 ters the vacuum chamber faster than the water pump can discharge it therefrom, the water inlet to the conduit between the receiver and vacuum chamber will be temporarily or partially closed to enable the wa- 45 ter pump to discharge the water from the vacuum chamber substantially as fast as it enters the same. Under such circumstances, the vacuum pump is relieved of its work un- 50 til the flow of water through the vacuum chamber is not faster than the water pump is capable of discharging it therefrom.

With these and other objects and advan- 55 tages in view, this invention consists in the several novel features of construction, ar-

rangement and combination of parts herein- 60 after fully set forth and claimed.

The invention is clearly illustrated in the drawing accompanying this specification in 65 which the figure is a view, partly in side ele- vation and partly in vertical longitudinal section, of a vacuum condensation pump il- 70 lustrating the preferred embodiment of the present invention.

Referring to said drawing, the reference 75 character 1 designates a receiver or collection tank having an inlet opening 2 adapted to be connected with the returns of a steam heat- 80 ing plant. As is well understood, water of condensation, vapor, air and other non-con- 85 densable gases flow into the receiver and col- 90 lect therein, the water filling the lower part of the receiver, and the vapors, air and other non-condensable gases collecting above the 95 water.

Usually the receiver is provided with a 100 float switch (not shown) for starting the pump motor when the water in the receiver rises above a predetermined level, and it is also usually provided with a pressure switch (not shown) for starting the pump motor in 105 case the vacuum in the receiver falls below the required one. These switches are set to stop the motor whenever the water in the receiver has been discharged therefrom down 110 to a predetermined level and when the vac- 115 um therein is up to normal.

Mounted adjacent the receiver and, as a 120 preference, on the top thereof, is a pump structure 3 which, in the preferred form of 125 the invention, has a casing 4 in which a pump shaft 5 is journaled in suitable bearing brackets, usually located at the ends of the 130 casing. The pump shaft is arranged to be 135 coupled to an electric motor (not shown) or it may be driven from any other suitable 140 source of power, as desired.

Mounted upon the shaft are the impellers 145 6 and 7 of a water pump 8 and a vacuum 150 pump 9, which may be of the types illustrated in the patent above referred to, or of any 155 other conventional types of water and vac- 160 um pumps. The vacuum pump shown is of the type which employs make-up water in its 165 operation and it receives the make-up water 170

from some part of the system. Supported above the pump casing 4 and, as a preference, carried by the structure thereof is a tank or receptacle 10 which contains a vacuum chamber 11 at one end, and in some cases an air discharge chamber 12 at the other end separated from the vacuum chamber 11 by a partition 13.

A water pipe 14 leads from a place adjacent the bottom of the vacuum chamber 11 to the inlet chamber 15 of the water pump 8, which pump discharges the water through its discharge end 16 into a pipe or other conduit (not shown) which leads back to the boiler or other place where it is desired to deliver the water. An air conduit 17 leads from a place adjacent the top of the vacuum chamber to the inlet chamber 18 of the vacuum pump, which pump discharges the air to the atmosphere and preferably through a discharge conduit 19 into the air discharge chamber 12. A check valve controlled air inlet pipe 20 leads from the outside atmosphere to the air conduit 17 and a check valve controlled air discharge pipe 21 leads from the air discharge chamber 12 to the outer atmosphere.

Leading from the receiver 1 to the vacuum chamber 11 is a conduit 22 through which water of condensation, vapors, air and non-condensable gases are removed from the receiver as a result of the vacuum created in the vacuum chamber 11 by the vacuum pump 9. The conduit 22 is in the form of a pipe which extends from a point adjacent the bottom of the receiver 1 to the vacuum tank 11 where it is provided with a head or elbow 23 opening to the interior of the vacuum tank.

Surrounding the end portion of the pipe 22 contained in the receiver 1 is a pipe 24 which is somewhat larger in diameter than the pipe 22, thus leaving an annular passage 25 between the pipes 22 and 24. The two pipes may be connected by suitable struts 26 or otherwise as desired, and the upper and lower ends of said outer pipe 24 are spaced away from the top and bottom walls of the receiver so as to furnish inlet ports to the interior of the outer pipe 24. As a preference, the outer pipe projects below the inner pipe 22 and permits the water contained in the receiver to flow into the inlet end of the pipe 22, whereas vapor, air and non-condensable gases flow into the upper end of the outer pipe 24 and are drawn down through the same and up through the pipe 22 as a result of vacuum produced therein by the vacuum pump 9.

Operating in connection with the outer pipe 24 is a valve 27 which is adapted to control the size of the water inlet and also to entirely close the same. The valve 27 is mounted upon a valve stem 28 which extends up through the pipe 22 and is connected to

and operated by a float mechanism, here shown in the form of a ball float 29 mounted upon a float stem 30 pivotally mounted in the head or elbow 23 as at 31 and extending through an eye 32 carried by the upper end of the valve stem 28. The valve stem is guided for vertical movement in suitable guide members contained in and supported by the pipe 22. It will be observed that so long as the water in the vacuum chamber 11 remains at a low level, the ball float will remain at its low limit with the valve 27 completely open, and that as the level of the water in the vacuum chamber rises, the ball float will be lifted correspondingly, thereby closing the valve 27 more or less until the level of the water in the vacuum chamber reaches a predetermined point, whereupon the valve 27 will entirely close the water inlet to the conduit 22.

In case the water enters the vacuum tank 11 considerably faster than the water pump can discharge it therefrom and lifts the ball float to an abnormally high place, the pumping action of the vacuum pump on the vacuum chamber is stopped and the vacuum pump is unloaded without reducing the vacuum in the vacuum chamber. To accomplish this, I provide a double acting valve 33 for closing the inlet opening 34 from the vacuum chamber to the air conduit 17 and simultaneously opening a port 35 between the air inlet pipe 20 and air conduit 17, which double acting valve is actuated by the float stem 30 which controls the valve 27. The double acting valve 33, as a preference, comprises valves 36 and 37 mounted on the two ends of a valve stem 38 which is guided in the ports 34 and 35. A loop member 39, formed with an elongated slot therein through which the float stem 30 extends, is provided upon the lower end of the double acting valve 33 and provides means whereby the float stem 30 may actuate the same, the elongated slot providing for a considerable amount of lost motion between the float stem 30 and double acting valve 33.

The make-up water for the vacuum pump 9 is furnished from the vacuum chamber 11 through a pipe 40 leading therefrom to the inlet chamber 18 of the vacuum pump 9, and, inasmuch as some water is discharged by the vacuum pump along with the air, the air discharge chamber 12 is provided for receiving this water where it may be stored until a considerable amount has been collected. This water is returned to the vacuum chamber through a port 41 formed in the partition 13 and controlled by a float valve 42. The float 43 of this float valve is carried upon the end of a stem 44 which projects from the valve 42. When the water rises to a predetermined height in the chamber 12, it lifts the float 43, thereby uncovering the port 41 and permit-

ting the water to discharge from the chamber 12 into the vacuum chamber 11.

In the operation of the vacuum condensation pump, and assuming the pump motor to be in operation, the vacuum pump 9 exhausts the air from the vacuum chamber 11 through the air conduit 17, so long as the valve 36 remains open, and this condition continues until the float 29 is raised sufficiently to close this valve. The vacuum produced by the vacuum pump extends to the conduit 22, the receiver 1 and the return pipes of the steam heating plant.

Water in the receiver 1 flows into the conduit 22 through the water inlet opening at the bottom thereof and vapor, air and other non-condensable gases, which are collected in the upper portion of the receiver enter the upper end of the pipe 24 and flow down through the annular passages between the same and the conduit 22 entering the lower end of the conduit 22 and mixing with the water which is passing up through the conduit 22. The vapors are condensed in the conduit by reason of their contact with the cooler water passing through the conduit, and by reason of their reduction in volume, a partial vacuum is caused in addition to the vacuum which is being produced by the vacuum pump.

The water, air and other non-condensable gases flow from the conduit 22 into the vacuum chamber 11 where they separate and the water is discharged therefrom through the conduit 14 by the water pump 8, and delivered back to the boiler or other place, and the air and non-condensable gases are discharged from the vacuum chamber through the air conduit 17 by the vacuum pump 9 and discharged through the air discharge chamber 12 to the outer atmosphere through the outlet pipe 21. Any water which is discharged by the vacuum pump into the chamber 12 collects therein until the float 43 is raised sufficiently to open the valve 42, whereupon the water flows back into the vacuum chamber 11.

Under ordinary circumstances, the water pump discharges the water from the vacuum chamber 11 as rapidly as it collects therein, but it sometimes happens that the volume of water which flows into the vacuum chamber slightly exceeds the capacity of the water pump, and, in such cases, the float 29 is raised accordingly, thereby closing the valve 27 more or less, as the case may be, and controlling the amount of water entering the conduit 22, so that the water pump may discharge the water from the vacuum chamber as rapidly as it collects therein. In the event that the volume of water entering the vacuum chamber greatly exceeds the capacity of the water pump, the level of the water in the vacuum chamber rises sufficiently to lift the float 29 until the float stem 30 engages the upper end of the slot of the loop

39 and closes the valve 36, simultaneously opening the valve 37, thus closing the port 34 between the vacuum chamber and the air conduit 17 and opening the air inlet port 35 from the outside air to the air conduit 17, thus unloading the vacuum pump, permitting it to run idly while the water pump continues to discharge water from the vacuum chamber. Under this condition, the water pump rapidly discharges the water from the vacuum chamber, and as the level of water therein lowers, the float 29 falls, thereby uncovering the water inlet at the lower end of the pipe 24 more or less as the case may be and permitting water to flow from the receiver through the conduit to the vacuum chamber.

As soon as the water pump discharges water from the vacuum chamber fast enough to permit the float to approach its lower limit, the float stem 30 engages the lower end of the slot in the loop 39, thereby drawing the double valve 33 down, closing the outside air inlet port 35 and opening the air inlet port 34, thus again placing the vacuum pump in communication with the interior of the vacuum chamber. In the ideal operation of the pump, the float 29 holds the valve 27 in a position regulating the size of the water inlet opening to the conduit 22 to one in which water enters the conduit 22 and vacuum chamber 11 no faster than the water pump can discharge it.

It is to be observed that by condensing the condensable vapors before they reach the pumping means a partial vacuum results from such condensation of the vapors which aids the pump in withdrawing the condensates from the system. Furthermore, in the present instance, the vapors are condensed by mixing the same with the water of condensation, thus eliminating the necessity for using additional water to effect the condensation of the vapors.

I claim as new, and desire to secure by Letters Patent:

1. Pumping apparatus comprising in combination a receiver for water, vapor and air, a vacuum chamber, a combined liquid and gas conduit leading from said receiver to said vacuum chamber and having a water inlet and a vapor and air inlet within the receiver, a pump for exhausting air from said vacuum chamber, and a pump for discharging water from said vacuum chamber.

2. Pumping apparatus comprising in combination a receiver for water, vapor and air, a vacuum chamber, a combined liquid and gas conduit connecting said receiver with said vacuum chamber and having a water inlet and a vapor and air inlet within said receiver, a rotary pump for exhausting air from said vacuum chamber whereby water, vapor and air flow from said receiver to said vacuum

chamber, and a pump for discharging water from said vacuum chamber.

3. Pumping apparatus comprising in combination a receiver for water, vapor and air, a vacuum chamber, a combined liquid and gas conduit leading from said receiver to said vacuum chamber and having a water inlet and a vapor and air inlet within the receiver, said vapor and air inlet leading to and discharging into the water inlet, a rotary pump for exhausting air from said vacuum chamber, whereby water, vapor and air flow from said receiver to said vacuum chamber through said conduit, and a centrifugal pump for discharging water from said vacuum chamber.

4. Pumping apparatus comprising in combination a receiver for water, vapor and air, a vacuum chamber, a conduit connecting said receiver with said vacuum chamber and having a valve controlled water inlet and a vapor and air inlet within the receiver, a centrifugal vacuum pump for exhausting air from said vacuum chamber, whereby water, vapor and air flow from said receiver to said vacuum chamber, and a pump for discharging water from said vacuum chamber.

5. Pumping apparatus comprising in combination a receiver for water, vapor and air, a vacuum chamber, a combined liquid and gas conduit leading from said receiver to said vacuum chamber and having a water inlet and a vapor and air inlet within the receiver, said vapor and air inlet leading to and discharging into the water inlet, a centrifugal vacuum pump for exhausting air from said vacuum chamber, whereby water, vapor and air flow from said receiver to said vacuum chamber, and a centrifugal water pump for discharging water from said vacuum chamber.

6. Pumping apparatus comprising in combination a receiver for water, vapor and air, a vacuum chamber, a combined liquid and gas conduit leading from said receiver to said vacuum chamber and having a water inlet and a vapor and air inlet within said receiver, said vapor and air inlet leading to and discharging into the water inlet, a rotary gas pump employing water for its pumping action for exhausting air from said vacuum chamber, whereby water, vapor and air flow from said receiver to said vacuum chamber through said conduit, and a pump for discharging water from said vacuum chamber.

7. Pumping apparatus comprising in combination a receiver for water, vapor and air, a vacuum chamber, a combined liquid and gas conduit leading from said receiver to said vacuum chamber and having a water inlet and a vapor and air inlet within said receiver, said vapor and air inlet leading to and discharging into the water inlet, a rotary gas pump employing water for its pumping action for exhausting air from said vacuum chamber, whereby water, vapor and air flow

from said receiver to said vacuum chamber through said conduit, and a centrifugal water pump for discharging water from said vacuum chamber.

8. Pumping apparatus comprising in combination a receiver for water, vapor and air, a vacuum chamber through which water and air flow, a conduit leading from said receiver to said vacuum chamber and having a water inlet and a vapor and air inlet within the receiver, a float operated valve for controlling said water inlet to the conduit and controlled by the level of liquid in the vacuum chamber, a vacuum pump for exhausting air from the vacuum chamber, and a water pump for discharging water from the vacuum chamber.

9. Pumping apparatus comprising in combination a receiver for water, vapor and air, a vacuum chamber through which water and air flow, a conduit leading from said receiver to said vacuum chamber and having a water inlet and a vapor and air inlet within the receiver, a valve for controlling said water inlet to the conduit, float mechanism for actuating said valve and having a float contained in said vacuum chamber, a vacuum pump for exhausting air from said vacuum chamber, whereby water, vapor and air flow from said receiver to said vacuum chamber through said conduit, and a water pump for discharging water from said vacuum chamber.

10. Pumping apparatus comprising in combination a receiver for water, vapor and air, a vacuum chamber, a conduit leading from said receiver to said vacuum chamber and having a water inlet and an air inlet within said receiver, a vacuum pump having an inlet opening from said vacuum chamber and operating to create vacuum in said vacuum chamber, whereby the water, vapor and air flow to said receiver through said conduit to said vacuum chamber, a float actuated valve for controlling the water inlet to the conduit having a float contained in said vacuum chamber.

11. Pumping apparatus comprising in combination a receiver for water, vapor and air, a vacuum chamber, a conduit leading from said receiver to said vacuum chamber and having a water inlet and a vapor and air inlet within said receiver, a vacuum pump, having an inlet port opening from said vacuum chamber, adapted to create vacuum in said vacuum chamber, whereby water, vapor and air flow from said receiver to said vacuum chamber through said conduit, a water pump for discharging water from said vacuum chamber, and float operated valves for controlling the water inlet to the conduit, and the air inlet port to the vacuum pump and having a float control in said vacuum chamber.

12. Pumping apparatus comprising in combination a receiver for water, vapor and air, a vacuum chamber, a conduit leading

from said receiver to said vacuum chamber and having a water inlet and a vapor and air inlet within said receiver, a vacuum pump, having an inlet port opening from said vacuum chamber, adapted to create vacuum therein, whereby water, vapor and air flow from said receiver through said conduit to said vacuum chamber, a water pump for discharging water from said vacuum chamber, a float operated valve for controlling the water inlet to said conduit, the float of said valve being contained in the vacuum chamber, and a valve operated by said float for controlling the inlet port between the vacuum chamber and the vacuum pump.

13. Pumping apparatus comprising in combination a receiver for water, vapor and air, a vacuum chamber, a conduit leading from said receiver to said vacuum chamber and having a water inlet and a vapor and air inlet within said receiver, a vacuum pump having an inlet passage provided with a port opening from said vacuum chamber and adapted to create vacuum therein, whereby water, vapor and air flow from said receiver through said conduit to said vacuum chamber, said passage having also a port opening to the outer atmosphere, a water pump for discharging water from said vacuum chamber, a float operated valve for controlling the water inlet to said conduit, the float of said valve being contained in the vacuum chamber, and valve mechanism for controlling the passage of air from said vacuum chamber to the vacuum pump and from the outside air to the vacuum pump, said valve mechanism being operated by the float.

14. Pumping apparatus comprising in combination a receiver for water, vapor and air, a vacuum chamber, a conduit for water, vapor and air leading from the bottom of the receiver to the vacuum chamber, a vapor and air inlet pipe of greater diameter than said conduit surrounding the latter within the receiver and providing an annular passage around the conduit having a vapor and air inlet at the top and a water inlet at the bottom, a float operated valve for controlling the water inlet to said conduit, the float of which is contained in the vacuum chamber, a vacuum pump for exhausting air from the vacuum chamber, and a water pump for discharging water therefrom.

15. Pumping apparatus comprising in combination a receiver for water, vapor and air, a pump for exhausting air from said receiver, a pump for discharging water from said receiver, a conduit leading from said receiver to the inlets of said pumps, and means for regulating the flow of water to the water pump.

16. Pumping apparatus comprising in combination a receiver for water, vapor and air, pumping means, a conduit leading from said receiver to said pumping means and hav-

ing a valve controlled water inlet and a vapor and air inlet within the receiver for varying the proportions of water and vapor and air entering said conduit.
